(57) **CLAIM**

The ornamental design for an adapter handle for inserting a rectal catheter, as shown and described.

DESCRIPTION

FIG. 1 is a top, rear and side elevational perspective view of an adapter handle for inserting a rectal catheter, illustrating a catheter positioned within the adapter handle shown in its environment of use;

FIG. 2 is a top, front and side elevational perspective view of the adapter handle for inserting a rectal catheter of FIG. 1 shown in its environment of use;

FIG. 3 is a top, rear and side elevational perspective view of the adapter handle for inserting a rectal catheter of FIG. 1; FIG. 4 is a top, front and side elevational perspective view of the adapter handle for inserting a rectal catheter of FIG. 1;

FIG. 5 is a rear view of the adapter handle for inserting a rectal catheter of FIG. 1;

FIG. 6 is front view of the adapter handle for inserting a rectal catheter of FIG. 1;

FIG. 7 is a rear, top and side elevational perspective view of the adapter handle for inserting a rectal catheter of FIG. 1; FIG. 8 is a bottom, front and side elevational perspective view of the adapter handle for inserting a rectal catheter of FIG. 1;

FIG. 9 is a left side elevational view of the adapter handle for inserting a rectal catheter of FIG. 1, illustrating a catheter positioned within the adapter handle shown in its environment of use;

FIG. 10 is a right side elevational view of the adapter handle for inserting a rectal catheter of FIG. 1 shown in its environment of use;

FIG. 11 is a bottom view of the adapter handle for inserting a rectal catheter of FIG. 1; and,

FIG. 12 is a top plan view of the adapter handle for inserting a rectal catheter of FIG. 1.

The dotted lines in FIG. 1, FIG. 8 and FIG. 9 show environment only and form no part of the claimed design.

1 Claim, 4 Drawing Sheets
